UNITED STATES PATENT OFFICE.

ALBERT H. MARANDA AND HENRY R. SNYDER, OF PITTSBURGH, PENNSYLVANIA.

GUARD-RAIL CLAMP.

1,163,431.

Specification of Letters Patent.

Patented Dec. 7, 1915.

Application filed February 20, 1915. Serial No. 9,577.

To all whom it may concern:

Be it known that we, ALBERT H. MARANDA and HENRY R. SNYDER, citizens of the United States, residing at Pittsburgh, in the 5 county of Allegheny and State of Pennsylvania, have invented certain new and useful Improvements in Guard-Rail Clamps, of which the following is a specification.

Our invention relates to guard rail clamps, 10 and particularly to clamps which permit of transverse adjustment of the guard rail with relation to the adjacent main rail to compensate for wear on the side of the head of the guard rail, and to facilitate locating the 15 guard rail in the proper position with relation to the frog which the guard rail protects.

It is well known that the side of the guard rail head becomes gradually worn off 20 due to the friction of the wheels of passing cars and trains, but it is desirable that the distance between the guard rail and the adjacent main rail be maintained constant regardless of such wear.

25 One object of our invention is the provision of means for adjusting the guard rail to compensate for such wear without necessitating the disturbing of any bolts, spikes or screws which enter the ties.

30 We will describe one form of clamp embodying our invention, and will then point out the novel features thereof in claims.

In the accompanying drawings, Figure 1 is a view showing in vertical transverse section a guard rail and the adjacent main rail, and one form of adjustable guard rail clamp embodying our invention. Fig. 2 is a top plan view of the parts shown in Fig. 1. Fig. 3 is a perspective view showing a removable filler comprising part of the filling means between the guard rail and the main rail. Fig. 4 is a perspective view showing a block comprising another part of the filling means between the guard rail and the main 45 rail.

Similar reference characters refer to similar parts in each of the several views.

50 Referring to Figs. 1 and 2, the reference character 1 designates a main track rail of a railway, and 2 a guard rail, both of which rails rest on a plate 3. This plate rests in turn on a switch tie 4 and is secured thereto by lag screws 5 or by other equivalent and suitable means. The other main track rail is 55 not shown in the drawings, but it is under-

stood that it lies to the right of rail 1 and is mounted on the same tie 4.

The main rail 1 is prevented from transverse movement to the left by means which I will now explain. The left hand portion 60 of plate 3 is bent back on itself at 3^a, and the end 3^b of this plate is cut at an angle as shown in Fig. 2. The end of the plate is held firmly against the main body of the plate by rivets 15. This end of the plate 65 forms a shoulder against which abuts a wedge or other suitable block 6 one side of which is cut at the same angle as the end 3^b of the plate. The opposite side of this block is shaped to approximately match the contour 70 of the rail 1 as shown in Fig. 1. This block 6 is provided with an elongated hole 7 through which pass two lag screws 5^a, which screws also pass through holes in the plate 3 and into the tie 4. It will be seen 75 that the transverse position of the rail 1 on plate 3 may be changed by loosening screws 5^a, sliding block 6 along the rail in one direction or the other, and again tightening screw 5^a. This adjustment of rail 1 is only 80 for the purpose of compensating for the wear on the right hand side of the head thereof, and is necessary only at very infrequent intervals.

The plate 3 is provided with a rib 3^c, 85 formed preferably by bending the plate upwardly and then downwardly as shown in Fig. 1, for a purpose which we will now explain.

Between the guard rail 2 and the rib 3^c 90 is a block 8, the left-hand face of which is shaped to approximately match the contour of the guard rail. This block is provided with a central strengthening rib 8^a, and with two chamfered portions 8^b on opposite sides 95 of the rib. Each of these chamfered portions is provided with a slot 9, and the plate 3 is provided with two unslotted holes which register with these slots in the block. Passing through each slot 9 and the registering 100 hole in the plate 3 is a round-headed bolt 10, the head of each bolt lying in a cavity provided in the tie for its accommodation. Each bolt is provided with a nut 10^a above the block. It will be seen that owing to the slots 105 9, the block 8 is capable of a limited movement along the plate 3, and that it can be rigidly clamped to the plate in adjusted position by tightening the nuts 10^a.

The adjustment of the block 9 and rail 2 110

is accomplished by means which we will now describe. The rib 3^e is provided with two holes 12 in which bolts 11 fit loosely, which bolts pass into clearance holes 8^e in the block 8. Mounted on each bolt between the rib and the block are two lock nuts 11^a. It will be seen that when the clamping bolts 10 are loose, the block 8 may be moved toward and away from the rib 3^e by loosening the lock nuts 11^a.

Located between the two rails 1 and 2 is an adjustable filling device by means of which the rails are always held firmly against blocks 6 and 8 respectively. As here shown, this device comprises a block 13 and one or more removable fillers 13^a, which parts are shown in perspective in Figs. 4 and 3 respectively. The side faces of the block 13 are shaped to approximately match the contours of the rails 1 and 2, and each filler 13^a is provided with a face similar to that of the block 13, that is with a face which matches the contour of the rails. The block and fillers are preferably interlocked by suitable means to prevent sliding of one part with relation to another; as here shown this is accomplished by providing a recess 14 in each side face of the block and providing each filler with a boss 14^a which fits into the recess in the block. If more than one filler is to be used on either side of the block, each filler is provided with a recess 14 into which the boss 14^a on the next outer filler will fit.

The manipulation of the device is as follows: When it is desired to change the position of the guard rail 2 on the plate 3, the nuts 10^a and 11^a are loosened. The rail 2 can be moved to the desired gage and one or more fillers 13^a inserted or extracted between the block 13 and one or both of the rails. After the adjustment is correct, nuts 10^a and 11^a are tightened, thus locking the guard rail in place.

One important feature of our invention lies in the fact that the adjustment of the guard rail may be accomplished without disturbing any screws or spikes which enter the ties; so that the adjustment occasions no wear whatsoever on the ties, and the necessity for tie plates is eliminated.

It is understood that for each guard rail there will be two or more clamps located on different ties, the number of clamps depending on the conditions of traffic.

Although we have herein shown and described only one form of clamp embodying our invention, it is understood that various changes and modifications may be made therein within the scope of the appended claims without departing from the spirit and scope of our invention.

Having thus described our invention, what we claim is:

1. An adjustable guard rail clamp comprising a fixed plate on which the guard rail

rests, said plate having an upwardly projecting rib, a block slidable on said plate and abutting against the guard rail, said block having a clearance hole and said rib having a hole extending therethrough and registering with the hole in the block, a screw passing loosely through the hole in the rib and into the hole in the block for adjusting the distance between the block and the rib bolts for clamping the block to the plate in adjusted position, lock nuts on the screw between the rib and the block, and means for holding the guard rail firmly against the block. 70 75

2. An adjustable guard rail clamp comprising a fixed plate on which the guard rail rests, said plate being bent upwardly on itself to form an upwardly projecting rib, a block slidable on said plate and abutting against the guard rail, means interposed between the block and said rib for adjusting the block toward and away from the rib, and means for holding the guard rail firmly against the block. 80 85

3. An adjustable guard rail clamp comprising a fixed plate on which both the guard rail and the adjacent main rail rest, one end of said plate being bent over on itself to form a shoulder on the top of the plate, a block interposed between said shoulder and the said main rail for locking the main rail against lateral movement in one direction, the plate being bent upwardly on itself to form a rib on the other side of said rails, a second block slidable on the plate and located between the guard rail and said rib, means interposed between the rib and the second block for adjusting the block toward and away from said rib, and adjustable filling means between the said main rail and the guard rail for holding the main rail firmly against the first block and the guard rail firmly against the second block. 90 95 100 105

4. In combination, a main track rail, a guard rail capable of transverse movement with relation thereto, adjustable filling means between the two rails comprising a block whose sides are shaped to substantially match the contour of the rails and a plurality of fillers adapted to be inserted between the sides of said block and the rails, each filler being shaped to substantially match the contour of the rails and each filler interlocking with the next filler or with the block, and means for locking the guard rail firmly against said filling means. 110 115 120

5. An adjustable guard rail clamp comprising a fixed plate on which the guard rail rests, said plate having an upwardly projecting rib, a block slidable on said plate and abutting against the guard rail, a screw and nut device interposed between the rib and the block for adjusting the distance between the rib and the block, and bolts for clamping the block to the plate in adjusted position. 125 130

6. An adjustable guard rail clamp comprising a fixed plate on which the guard rail rests, said plate having an upwardly projecting rib, a block slidable on said plate and abutting against the guard rail, a screw and nut device interposed between the rib and the block for adjusting the distance between the rib and the block, and means independent of the screw and nut device for clamping the block to the plate in adjusted position. 10
7. An adjustable guard rail clamp comprising a fixed plate on which the guard rail rests, said plate having an upwardly projecting rib, a block slidable on said plate and abutting against the guard rail, a screw and 15
- nut device interposed between the rib and the block for adjusting the distance between the rib and the block, means independent of the screw and nut device for clamping the block to the plate in adjusted position. 20

In testimony whereof we affix our signatures in presence of two witnesses.

ALBERT H. MARANDA.
HENRY R. SNYDER.
